INVENTOR.
Edgar R. Hill.

Charles E. Wimmer

ATTORNEY.

UNITED STATES PATENT OFFICE.

EDGAR R. HILL, OF OAK PARK, ILLINOIS.

IRONING MACHINE.

Application filed January 12, 1922. Serial No. 523,622.

To all whom it may concern:

Be it known that I, EDGAR R. HILL, a citizen of the United States, residing at Oak Park, county of Cook, State of Illinois, have 5 invented a certain new and useful Improvement in Ironing Machines, and declare the following to be a full, clear, and exact description of the same, such as will enable others skilled in the art to which it pertains 10 to make and use the same, reference being had to the accompanying drawings, which form a part of this specification.

This invention relates to ironing machines and the object of the invention is to provide 15 an ironing machine consisting of a feed roller over which clothes are fed and brought into contact with a heated ironing shoe which is stationarily positioned in the frame of the ironing machine. Another object 20 of the invention is to provide a means for moving the roller toward or from the heated ironing shoe the said means also moving the driving mechanism into or out of driving engagement. A further object of 25 the invention is to provide a drive for an ironing machine which is very simple and which may be connected or disconnected by movement of a lever, the said lever being primarily arranged for moving the roller of 30 the ironing machine toward and from the ironing shoe. Another object of the invention is to provide a worm for driving the ironing machine which, when the roller is moved toward the ironing shoe is moved to 35 driving engagement with worm gear, through which the machine is driven and, when the roller is moved away from the ironing shoe, the worm is moved out of mesh with the worm gear. These objects 40 and the several novel features of the invention are hereinafter more fully described and claimed and the preferred form of construction by which these objects are attained is shown in the accompanying drawings in 45 which—

Fig. 1 is an end view of an ironing machine embodying my invention.

Fig. 2 is a similar view showing the mechanism in the driving position.

Fig. 3 is an enlarged section taken on line 3—3 of Fig. 2.

Fig. 4 is an enlarged section of the yieldable connection by which the feed roller may be moved toward or from the ironing shoe.

The ironing machine comprises a frame

1 having supporting legs 2 and having a flat table top 3 as shown in dotted lines in Figs 1 and 2. The framework 1 is provided with a bracket 4 on which is mounted an electric 60 motor 5 for driving the ironing machine. The motor 5 is provided with a shaft 6 having a flange 7 on the end thereof provided with a series of pins 8 extending from the face thereof. These pins 8 engage in radial 65 slots provided in the member 9 on the end of the shaft 10. The shaft 10 is rotatably mounted in bearings 11 on a plate 12 and a worm 13 is secured to the shaft 10 between the bearings 11. This plate 12 is provided 70 with a pivot 14 which is rotatably mounted in the frame 1 so that when the plate 12 is swung down on the pivot 14 as shown in Fig. 1, the worm 13 is out of mesh with the worm gear 15 and when the plate 12 is 75 swung up as shown in Fig. 2 the worm 13 meshes with the worm gear 15. In this position the mechanism is in the driving position and a small gear 16 is provided on the shaft 17 of the gear 15 and this small gear 80 16 meshes with a larger gear 18 which is secured to the outer end of the shaft 19. An arm 60 shown in Figs. 1 and 2 is rotatably mounted on each end of the shaft 17 and at the upper ends are provided with bearings 85 for the shaft 19 in which the shaft 19 is rotatably mounted and the shaft 19 is movable through a slot 21 provided in each end of the frame. The shaft 19 is provided with a bearing 20 on each end thereof as shown in 90 Figs. 1 and 2 in which the shaft is rotatably mounted and the purpose of which is herein-after more fully described. Between the ends of the frame is a roller or drum 22 which is secured to the shaft 19 and which 95 is preferably covered with several layers of cloth or a cloth pad as may be desired. This roller 22 is the feed roller for the machine and the clothes to be ironed are placed on the table top 3 and are fed onto the roller 100 therefrom. An ironing shoe 23 is secured to each end of the frame and extends from one end to the other and the face 24 of the ironing shoe is formed on a radius equal to the radius of the drum or roller 22, the said shoe being flared outwardly at 25 so that the clothes will not catch thereon when being carried around by the roller. This ironing shoe is provided with a sheet metal casing 105 26 which encloses a gas burner 27 for heating the shoe, the said gas burner being adapted 110 for connection with a gas feed line as will be

readily understood. The bearing 20 is provided with a boss 28 on one side thereof and a shaft 29 is secured therein by a pin 30 as shown in Fig. 4. This shaft 29 is provided 5 with a slot 31 therethrough and an aperture is provided in the end for the stud 32 which is threaded in to a member 33. This stud 32 is provided with a pin 34 adapted to ride in the slot 31 and prevent the members 29 10 and 32 from pulling apart, as will be readily understood. The member 33 is provided with a recess 35 in which the end of the shaft 29 may move and the said member is also threaded on the outside at 36 to receive a nut 15 37. A coiled spring is interposed between the nut 37 and the shoulder 38 of the boss 28 and by adjusting the nut 37 on the threads 36 the tension of the spring 39 may be increased or decreased as desired. This 20 spring normally holds the members 29 and 33 apart with the pin 34 engaging the end of the slot 31. The member 33 is provided with a short shaft or stud 40 rotatably mounted in the end thereof which also ex- 25 tends through the end of a lever 41 and the end of an arm 42, the shaft or stud 40 being held in place by a cotter pin 43. The lever 41 is connected by means of a round rod 44, shown in dotted lines, to a similar lever 41 30 at the opposite end of the ironing machine frame and the levers 41 are pivoted on a stationary pivot 45 mounted on the frame 1. The arm 42 at the lower end is pivotally connected at 46 to the end of a spring arm 35 47 which is attached to a cam 48 shown more particularly in Fig. 3. The cam 48 is pivotally mounted on a bolt 49 which is secured in the frame 1 and the member 12 is pro- 40 vided with a recess 50 for the said cam. The member 12 is also provided with a slot 51 as shown in Fig. 3 through which the bolt 49 extends and this bolt acts as a guide for the swinging of the member 12 on the pivot 14. When the rod 44 and levers 41 are raised 45 from the position shown in Fig. 1 to that shown in Fig. 3 the members 33 and 29 are forced to the right thus moving the bearings 20 and shaft 19 on the arms 60 to the right of the slot 21 and moving the roller 22 to 50 engagement with the face 24 of the ironing shoe. Should a thick piece of clothing be positioned between the roller 22 and the shoe when the lever 41 is raised the roller will not be moved as far as usual and the portion 55 33 will telescope over the member 29 thus compressing the spring 39 and thereby pressing the roller toward the face of the iron. When the rod 40 is moved to move the roller as described the arm 42 is moved down- 60 wardly thereby turning the cam 48, on which the member 12 is supported, on its pivot 49 which raises the worm 13 into mesh with the worm gear 15, the slot 51 allowing such movement of the member 12. 65 By this means when the roller is moved

toward the ironing shoe the driving mechanism drives the roller so that the clothes thereon cannot remain in stationary contact with the heated iron. The arm 47 is made of 70 spring metal so that should the teeth of the worm engage the outer faces of the teeth of the worm gear the lever 42 may continue downwardly without breaking any of the parts and, as the worm gear is rotated it will immediately move into the spaces between the 75 teeth of the worm gear thus allowing the member 12 to move upwardly to the normal driving position shown in Fig. 2. To stop the driving mechanism it is only necessary to move the rod 44 and levers 41 to the position 80 shown in Fig. 1 which draws the roller 22 mounted on the arms 60 away from the ironing shoe and moves the member 12 and worm 13 out of driving engagement with the worm gear 15. A casing is provided for 85 the mechanism on the outside of the frame ends 1, though not here shown, and acts as a guard to prevent the clothing from coming in contact with the gears.

From the foregoing description it becomes 90 evident that the device is very simple and efficient in operation, will not easily get out of order, is composed of comparatively few parts and is of consequent low manufacturing cost and provides a device which accom- 95 plishes the objects described.

Having thus fully described my invention, its utility and mode of operation, what I claim and desire to secure by Letters Patent of the United States is—

1. In an ironing machine, a frame, an ironing shoe extending between the ends of the frame, means for heating the ironing shoe, a pivoted arm at each end of the frame, a feed roll rotatably mounted in the ends of the said arms, a lever pivotally mounted on each end of the frame, yieldable means connecting the end of each lever with the shaft of the feed roll, a driving mechanism for rotating the feed roll comprising a worm and gear, means for rotating the worm, a plate pivotally mounted at one end of the frame and rotatably supporting the worm, the said plate being provided with a recess, a cam rotatably mounted in the recess and provided with a spring arm, a bar pivotally connecting the end of one lever with the spring arm of the cam, the arrangement being such that upon upward movement of the levers to move the feed roll toward the ironing shoe the worm is moved into mesh with the worm gear and upon downward movement of the levers to withdraw the feed roll from the ironing shoe the worm is moved out of mesh with the worm gear. 110

2. In an ironing machine, a frame, an ironing shoe supported by the frame, means for heating the ironing shoe, a rotatable feed roll adapted to be moved into or out of engagement with the shoe, a lever pivot- 120 125 130

- ally mounted at the end of the frame, a yieldable means connecting the lever and the feed roll whereby upward movement of the lever moves the feed roll into engagement with the ironing shoe and downward movement of the lever withdraws the roll from engagement with the shoe, a worm and a worm gear for driving the feed roll, a plate pivoted to swing in a vertical plane supporting the worm, a connection between the said worm plate and the said pivoted lever whereby upward movement of the lever to cause engagement of the feed roll with the shoe moves the plate and causes engagement of the worm with a worm gear, and movement of the lever in the opposite direction withdraws the feed roll from the shoe and moves the plate to disconnect the worm from the worm gear.
3. In an ironing machine, a frame, an ironing shoe extending between the ends of the frame, means for heating the ironing shoe, a rotatable feed roll adapted to be moved into or out of engagement with the ironing shoe, a lever adapted upon upward movement to move the feed roll into engagement with the ironing shoe, and upon downward movement to withdraw the feed roll from engagement with the ironing shoe, a driving mechanism comprising a worm and worm gear, a plate pivotally mounted on the end of the frame and rotatably supporting the worm and shaft therefor, an electric motor for rotating the worm, a flexible joint between the shaft of the worm gear and the shaft of the electric motor, and means operable by upward movement of the lever to move the worm into mesh with the worm gear, and upon downward movement of the lever to move the worm out of mesh with the worm gear.
4. In an ironing machine, an ironing shoe extending between the ends of the frame, means for heating the ironing shoe, a rotatable feed roll adapted to be moved into or out of engagement with the ironing shoe, a control mechanism comprising a lever at each end of the frame, a bar connecting the said levers whereby upward movement of the levers by the bar moves the feed roll into engagement with the ironing shoe and downward movement of the levers by the bar moves the feed roll out of engagement with the ironing shoe, a driving mechanism comprising a worm and worm gear, a member connecting one of the levers with the worm whereby upward movement of the levers moves the worm into mesh with the worm gear and downward movement of the levers disengages the worm from the worm gear and means for rotating the worm.
5. In an ironing machine, a frame, an ironing shoe extending between the ends of the frame, means for heating the ironing shoe, a rotatable feed roll adapted to be moved into or out of engagement with the ironing shoe, a driving mechanism for rotating the feed roll comprising a worm gear and a worm mounted to swing in a vertical plane, means for moving the worm into mesh with the worm gear upon operation of the means for moving the feed roll toward the ironing shoe, means for disengaging the worm from the worm gear upon operation of the means for moving the feed roll out of engagement with the ironing shoe, and means for rotating the worm.
6. In an ironing machine, a frame, an ironing shoe extending between the ends of the frame, means for heating the ironing shoe, a rotatable feed roll adapted to be moved into or out of engagement with the ironing shoe, a worm and a worm gear for driving the feed roll, means for rotating the worm, means whereby movement of the feed roll toward the ironing shoe moves the worm into mesh with the worm gear, and withdrawal of the feed roll from the ironing shoe moves the worm out of mesh with the worm gear and means for rotating the worm.
7. In an ironing machine, a frame, an ironing shoe extending between the ends of the frame, a fixed table on the frame, a rotatable feed roll between the table and the shoe and adapted to be moved into or out of engagement with the shoe, means for heating the shoe, a driving mechanism for rotating the feed roll, a bar extending across the front of the frame and having an arm at each end thereof pivoted to the respective frame ends permitting the bar to be moved upward toward or downward from the table, a spring toggle connection between the pivoted arms and the feed roll whereby downward movement of the bar draws the feed roll and from the shoe and upward movement brings the same into engagement with the shoe, a worm wheel for driving the feed roll, and a worm brought into and out of engagement with the worm wheel by moving the bar upward or downward respectively.
8. In an ironing machine, a frame, an ironing shoe extending between the frame ends at the rear, a stationary table between the frame ends at the front, a feed roll rotatably supported between the shoe and table, a bar having an arm at each end pivoted to the respective frame ends, a spring connection between the end of each arm and the feed roll whereby on moving the bar upward toward the table the feed roll is brought to engagement with the shoe and by movement in the opposite direction the feed roll is withdrawn from the shoe, a worm wheel, a shaft therefor, a gear on the shaft, a gear on the feed roll with

which said last named gear meshes and a worm for driving the worm wheel, a pivoted plate supporting the worm, a link extending from the forward part of an arm of the operating bar and pivotally connected with the plate whereby when the lever is raised to bring the roll into engagement with the shoe the plate is turned causing the

worm to mesh with the worm wheel and when the lever is moved to withdraw the roll from the shoe turns the plate and disengages the worm from the worm wheel.

In testimony whereof, I sign this specification.

EDGAR R. HILL.
